[57] CLAIM

The ornamental design for a digital thermometer, substantially as shown and described.

DESCRIPTION

FIG. 1 is a perspective view of a digital thermometer showing our new design;

FIG. 2 is a front elevational view thereof with the probe unit omitted for ease of illustration, the rear being flat, plain, and unornamented;

FIG. 3 is a left side elevational view of FIG. 2;

FIG. 4 is a right side elevational view of FIG. 2; and

FIG. 5 is a top plan view of FIG. 2, the bottom plan being a mirror image thereto.
